LIGHTING FIXTURE ATTACHMENT FOR VEHICLE DASHBOARDS

Joseph T. Andrews, 5734 Thunderhill Road,
Columbia, Md. 21043

Filed Apr. 15, 1975, Ser. No. 568,326

Term of patent 14 years

Int. Cl. D26—06

U.S. Cl. D48—32 B

Fig. 1

Fig. 2

Fig. 3

*Fig. 4**Fig. 5*FIG. 1 is a front elevational view of a light fixture attachment for vehicle dashboards showing my new design, the dashboard being shown in broken lines for illustrative purposes only; and

FIGS. 2-5 are top plan, bottom plan, rear elevational and right side elevational views respectively of the fixture.

I claim:

The ornamental design for a lighting fixture attachment for vehicle dashboards, as shown and described.
